Ex

OF D 19,767

WILLIAM ADAMS, OF PHILADELPHIA, PENNSYLVANIA.

DESIGN FOR A SETTEE.

Design No. 19,767, dated April 22, 1890.

UNITED STATES PATENT OFFICE.

WILLIAM ADAMS, OF PHILADELPHIA, PENNSYLVANIA.

DESIGN FOR A SETTEE.

SPECIFICATION forming part of Design No. 19,767, dated April 22, 1890.

Application filed March 29, 1890. Serial No. 345,894. Term of patent 3½ years.

To all whom it may concern:

Be it known that I, WILLIAM ADAMS, a citizen of the United States, residing at the city of Philadelphia, in the county of Philadelphia and State of Pennsylvania, have invented and produced a new and original Design for Settees or Benches, of which the following is a specification, reference being had to the accompanying photograph, forming part hereof, which illustrates in perspective a bench or settee embodying the features of my invention.

The leading features of my design for settees or benches consist of foliations, scrolls, and ornamental configurations formed in and disposed above the paneled back of the settee or bench, and in the shape and ornamental contour of the legs, arms, and seat of the settee, all of which are illustrated in the accompanying photograph and hereinafter more fully described.

Referring now to the accompanying photograph for a further description of my design, A are embossed scrolls included in or surrounding conventional fleur-de-lis A' and surmounting each of the panels B.

A² are curved frets connecting the scrolls A together and to the top of the panels B.

The embossed scrolls, foliations, or ornamental configurations C are disposed within

the panels B around foliated or leaf-like centers C'.

D are curved legs connected in pairs at or near the lower portion thereof by two similarly-disposed arches E.

F are curved and sloping arms terminating in convoluted portions or spirals G.

H is the latticed seat of the bench or settee, having the scalloped or serrated fret-work frieze I depending from the front and sides thereof.

It may be remarked that the beauty and salability of the benches or settees are greatly enhanced by the above-described configurations and foliations.

Having thus particularly described the characteristic features of my design, what I claim as new, and desire to secure by Letters Patent, is—

The design for a settee, bench, &c., substantially as herein described and shown.

In witness whereof I have hereunto set my signature in the presence of two subscribing witnesses.

WILLIAM ADAMS.

Witnesses:

GEO. W. REED,
RICHARD C. MAXWELL.
